UNITED STATES PATENT OFFICE

2,038,717

CALCULATING MACHINE

Raymond A. Christian, Dayton, Ohio, assignor to
 The National Cash Register Company, Dayton,
 Ohio, a corporation of Maryland

Application July 29, 1932, Serial No. 626,152

24 Claims. (Cl. 235—60)

This invention relates to accounting machines and the like, but more particularly to improvements in machines of the well-known Ellis type, such as are set out and described in Letters Patent of the United States Nos. 1,197,276 and 1,197,278, issued September 5, 1916 to Halcolm Ellis and Patent No. 1,203,863, issued November 7, 1916 to Halcolm Ellis, and Patent No. 1,819,084 issued to Emil John Ens, August 18, 1931.

10 The primary object of this invention is to produce a machine adapted for use in banks and other business institutions, where debits and credits are constantly being made upon individual accounts, with an accounting machine which makes such entries in logical order, one under the other, much the same as a bookkeeper would hand-post them.

Another object is to furnish means whereby the selection of a particular totalizer for addition, subtraction or totalizing transactions causes the total of each of the above transactions to be automatically stored in separate totalizers.

Still another object is to provide means for automatically printing subtractive items in a distinctive color.

A further object is to supply means for locking the overdraft mechanism when a particular totalizer has been previously selected for addition or subtraction.

30 Another object is to provide novel non-repeat means for the overdraft mechanism.

Still another object is to provide means for simultaneously unlocking the machine starting bar and restoring either the additive or subtractive selecting means of a particular totalizer to ineffective position.

A further object is to provide means whereby selection of a particular totalizer for a balancing operation automatically tabulates the traveling carriage so that the printing of balances will be offset from other entries printed in the same column.

A still further object is to furnish means to prevent operation of the machine for addition or subtraction when the traveling carriage is in the balance or off-set printing position.

Another object of the instant invention is to provide interlocks between the various totalizer controlling keys, between said controlling keys and the machine releasing mechanism, between certain of the totalizer control keys and the overdraft keys, and between certain totalizer control keys and the automatic tabulating mechanism.

55 With these and incidental objects in view, the invention consists of certain novel features of

construction and combinations of parts, the essential elements of which are set forth in appended claims and a preferred form of embodiment of which is hereinafter described with reference to the drawings which accompany and form part of this specification.

Of said drawings:

GENERAL DESCRIPTION

The instant invention is shown incorporated in the well known Ellis accounting machine, which is fully illustrated and described in the patents referred to at the beginning of this specification.

The machine of the instant invention is equipped with a traveling carriage and if desired may also be equipped with typewriter attachment. This machine is supplied with four totalizers, one of which is adapted for both addition and subtraction.

In banking institutions it is customary to balance each checking account daily. This is accomplished in the majority of such institutions by the use of accounting or bookkeeping machines. With but few exceptions these institutions use a system requiring a ledger or posting sheet for each individual account. These ledger sheets are generally the full width of the traveling carriage and are divided into a plurality of 25 vertical columns several of which are used for the listing of checks issued against the particular account, one or more of said columns being used for the posting of deposits and another column for balancing the account.

Heretofore the practice has been to work across the ledger sheet from left to right in a horizontal line, tabulating the traveling carriage after each entry. The machine of the instant invention uses a ledger sheet divided into a plurality of vertical spaces the same as former machines, but instead of listing the items horizontally across the sheet all entries are listed in vertical alignment, one under the other, until one columnar division is filled. The traveling carriage 40 is then tabulated to the next column where entries are made as before, and so on. This method of listing the different entries makes for speedier machine operation, ease in checking or verifying an account, and also renders the machine adaptable for use in department stores or similar businesses with very little mechanical change.

The machine of the instant invention is supplied with a tally roll mechanism mounted independent of the traveling carriage. The inking ribbon has been reflexed in such a manner as to straddle the web of the tally roll, making it possible to print positively upon the tally web and ledger sheet simultaneously. The tally web is 55 at all times between the printing type and the ledger sheet, the printing upon the ledger sheet being done through the tally web by means of the reflex ribbon which eliminates the use of carbon duplicates for proof purposes. This machine has also been equipped with an overdraft mechanism, which automatically transposes a complementary overdraft into a positive amount and prints such positive amount in a distinguishing manner.

Mechanism has been devised whereby the depression of a check or debit key shifts the ribbon mechanism to a position where debit items will be printed in a distinctive color. All other items are easily distinguishable by means of 70 characteristic symbols printed in horizontal alignment therewith.

As previously stated, the instant machine is equipped with four totalizers. The calculation of an account takes place in the add-subtract 75

totalizer, the remaining three totalizers being used for the storing of totals of debits, credits and balances.

In horizontal posting machines different items are placed in designated columns and selection of the different storage totalizers is generally accomplished by means of the traveling carriage in tabulated positions thereof. However, in the instant machine where all items are posted vertically, selection of the storage totalizers is accomplished by means of mechanism connected to the control keys for the add-subtract totalizer. This necessitated the addition of interlocking mechanism between the various control keys, between the control keys and the overdraft mechanism, and between the control keys and the machine releasing mechanism.

The machine embodying the present invention is supplied with a dating device, the setting levers of which are locked against manipulation each time the machine is released for operation.

The present machine is also equipped with an injector device for revolving the platen roll rapidly to facilitate the insertion and ejection 25 of ledger sheets or other matter.

In the detailed description to follow the above mechanisms will be thoroughly explained.

DETAILED DESCRIPTION

30 Operating mechanism and keyboard

The machine embodying the instant invention is an accounting machine of the well-known Ellis type. The mechanism of this machine is supported between two main frames 60 and 61 (Figs. 2 and 3) mounted parallel to each other upon a base plate (not shown). A machine case 63 (Figs. 3 and 16), also secured to the base plate, encloses the mechanism of the machine and supports the traveling carriage. Mounted 40 to slide laterally upon ways secured to the machine case 63 is a traveling carriage 64 carrying a revoluble platen roll 65 (Figs. 3, 7, 10 and 16).

Secured to the base plate is an electric motor 45 (not here shown) of the type illustrated and described in the United States Patent No. 1,601,102, issued September 28, 1926 to F. W. Bernau. This motor is of the constantly running type and operates the driving member of a clutch (not shown). The driven member of the clutch is operatively connected to said driving member by the depression of a starting bar 66 (Figs. 1 and 2), and travels a complete revolution with said driving member whence it is automatically disconnected therefrom by mechanism not here shown but fully set out in the above referred to Bernau patent.

A link 67 (Fig. 2) operatively connects the clutch driven member with an arm 68 secured 60 to a main operating shaft 69 journaled in the main frames 60 and 61. Fast in the arm 68 is a stud 70 which carries a roller 71 embraced by a cam slot 72 in a cam plate 73 secured to a shaft 74 also journaled in the frames 60 and 61. The stud 70 extends through the arm 68 and has pivoted on its left end another roller (not shown), arranged to cooperate in the usual manner with a cam race 75 formed in an alining arm 76, flexibly connected to a shaft 77 journaled in 70 the main frames. Secured to a printer shaft 80 (Figs. 2 and 19) is a lever 81 having pivoted thereon an arm 82 retained in position by a spring 83. Pivoted to the arm 82 is a shiftable link 84 normally operatively connected to the 75 arm 68 but adapted to be disconnected there-

from during part of an overdraft operation in order to disable the printing mechanism at that time.

Each time the machine is operated the shaft 69 (Fig. 2) due to its connection to the driven member of the clutch is oscillated through an angle of approximately 60 degrees, the initial movement being counter-clockwise, but clockwise as viewed in Figs. 16 and 17. Upon the counter-clockwise movement of shaft 69 (Fig. 2), the arm 68, roller 71 and cam plate 73, also rocks the shaft 74 counter-clockwise. The roller (not shown) on the left end of the stud 70, coacting with the cam roll 75, rocks the arm 76 and the shaft 77 in a clockwise direction. The return 15 movement of shaft 69, through the means above described reverses the movements of shafts 84 and 77. Oscillation of the arm 68, through the link 84, arm 82 and lever 81 oscillates the shaft 80. 20

Referring to Fig. 3, pivoted on the shaft 74 is a plurality of multi-armed reducing levers 85 urged counter-clockwise by a plurality of springs 86 against the bar 87 on the leading frame 88 secured to the shaft 74. Each reducing lever 85 has therein a stud 89 adapted to cooperate with a slot 90 in each of a plurality of actuating racks 91 reciprocably mounted by means of a plurality of slotted crossbars 92 and 93 which extend the width of the machine and 30 are supported by the main frames 60 and 61. Each reducing lever 85 has a toothed sector 94 arranged to cooperate with an alining bar 95 secured to the shaft 77. Each lever 85 has an arm 96 connected by a link 97 to a printing segment 35 98 pivoted to a printing arm 99 loosely mounted on the shaft 80. Another arm 100 (Fig. 3) on each lever 85 has a stud 101 arranged to cooperate with an arcuate surface 102 of a tail 103 on a lever 104 mounted upon a pin 105 in a slotted block (not shown) which is supported between two plates (not shown) of the printer frame. The upper ends of the levers 104 are hook-shaped to cooperate with projections 106 on driving arms 107 pivoted on the shaft 80 and slotted to embrace 40 studs 110 secured in the arms 99. Secured to the shaft 80 is a yoke 111 having therein a bail 112 adapted to cooperate with a nose 113 on each arm 107. Pivoted on each of the arms 99 is a pawl 114 notched to cooperate with projections 45 115 on the arms 107 and having tails 116 held in contact with hubs of the arms 107 by springs 117 tensioned between the pawls 114 and the yoke 111. Pivoted within the printer frame is a 50 printer trigger 118 having an angular rail 119 adapted to cooperate with a projection 120 on each of the arms 107 for a purpose to be later described. 55

The machine of the instant invention is 60 equipped with a plurality of amount keys 121 (Figs. 1 and 3) arranged in denominational rows representing units of cents, tens of cents, units of dollars, etc. These keys are flexible in that the depression of an amount key will release any key previously depressed in the same denominational row. Each key 121 carries a square stud 122 arranged to cooperate with one of a plurality of graduated steps 123 carried by the actuator racks 91. There is an actuator rack 91, reducing lever 85 and printing segment 98 for each 65 denominational row of amount keys. 70

As the different amount banks function in exactly the same manner, the description of one such amount bank will be used as representative of all the amount banks. 75

Calling attention to Fig. 3, depression of one of the amount keys 121 in add, non-add or subtract operations places the stud 122 in the path of a particular step 123 on the actuator rack 91. 5 Oscillation of the shaft 74 as previously explained, causes the leading frame 88 to be rocked first in a counter-clockwise direction, carrying therewith the reducing levers 85, whereupon the racks 91 move rearwardly until the step 123 corresponding to the amount key depressed contacts the stud 122 in said amount key 121, stopping the rearward movement of the rack 91 and its reducing lever 85. The leading frame 88 continues its counter-clockwise movement uninterrupted, 15 flexing the spring 86.

In case no key is depressed in an amount bank, the rack 91 and its reducing lever 85 for that bank are retained in their forward or zero position by means of the usual latch, (not shown) 20 cooperating with said rack, said latch being released in add, non-add and subtract operations of the machine by depression of any amount key in that bank. There are no steps on the racks 91 for the 9 amount keys, depression of which 25 merely unlatches the racks, which are then free to move rearward with the leading frame 88 until stopped by projections 124 contacting the bar 92.

The printing segments 98 are positioned during 30 the rearward movement of the actuator racks 91 by means of the link 97. When any of the reducing levers 85 is moved out of zero position, the stud 101 in the arm 100 coacts with the arcuate surface 102 on the associated lever 104 35 rocking it counter-clockwise to disengage the hook on the lever 104 from the projection 106, which in turn releases the driving arm 107 for a printing operation.

Initial clockwise movement of the shaft 80 40 rocks the yoke 111 clockwise, flexing the springs 117. Near the end of the initial movement of the shaft 80 and after the leading frame 88 has completed its initial movement to permit proper setting of actuators 91, a crank (not shown) secured 45 to said shaft 80 engages an arm (not shown) secured to the printer trigger 118 to rock said trigger counterclockwise to release all the arms 107 from which the hooks 104 have been previously disengaged, as explained above, to the action of the 50 springs 117. The springs 117 then force the released arms 107 and 99 clockwise, thereby causing the printing segment 98 to be brought sharply into contact with the platen roll 65, causing an impression to be made upon matter inserted between said platen roll and the printing type. 55

Each of the levers 104 carries an angular projection 125 arranged to extend in the path of the adjoining lever 104 for the next highest order amount bank, to the end that depression of a 60 key in the units of dollars bank through the rearward movement of the actuator rack 91 and consequential rocking of the reducing lever 85 releases not only the printing arm 107 for the units of dollars bank, but through the projections 125 and the levers 104 also releases the arms 107 for all lower order denominations. This 65 results in zeros being printed for all lower denominations, but eliminates zeros from all higher denominations. This so-called zero elimination 70 mechanism is old in the art and has been fully explained in former Ellis patents.

Totalizer

The instant machine has four totalizers arranged in vertical pairs at the rear of the machine

(Fig. 3). For convenience these totalizers will be numbered in the same manner as has heretofore been the custom. The upper front totalizer will be called No. 1, lower front No. 2, upper rear No. 3 and lower rear totalizer No. 4. The No. 1 5 totalizer is arranged for both addition and subtraction, the three remaining totalizers being adapted for addition only in the instant machine.

In adding, non-adding and subtracting operations the actuators 91 are positioned upon depression of the amount keys 121 and function exactly alike for each of the above three operations. Each of the totalizers carries a plurality of wheels 108, one for each denominational row of amount keys, which are adapted to cooperate with teeth 15 in the actuator racks 91. In adding operations the totalizer wheels are engaged with the actuator racks after said racks have finished their initial movement rearward. The final or clockwise movement of the leading frame 88 returns the actuators 20 to their home positions, rotating any engaged totalizer wheels 108 in the proper direction for addition, commensurate with the value of the amount set up on the keyboard. In subtracting operations the wheels of the No. 1 totalizer are 25 meshed with the racks 91 before the latter start their rearward movement, so that said totalizer wheels will be rotated properly for subtraction by the initial movement of the racks. The totalizer wheels are then disengaged from the racks before 30 they start their return movement forward.

The No. 1 totalizer is equipped with a dual transfer or carrying mechanism, which is normally retained in adding position but is automatically shifted to subtract position when said 35 totalizer is selected for a subtract operation. This carrying mechanism, while not shown in this application, is fully set out and described in the Ellis Patent No. 1,203,863, referred to at the beginning of this specification. The remaining 40 totalizers are equipped with a carrying mechanism similar to that shown and described in Patent No. 1,536,757, issued May 5, 1925 to F. W. Bernau. Therefore, it is thought unnecessary to describe this mechanism in this specification. 45

In non-add operations the totalizers are retained out of mesh with the racks 91, movement of which serves only to position the printing segments commensurate with the value of the amount keys depressed. In totalizing operations the 50 selected totalizer is meshed with the actuator racks 91 prior to their initial movement rearward, which movement rotates the totalizer wheels 108 until stopped at zero by one of two of the usual diametrically opposed projections (not here 55 shown) thereon coming in contact with a stop (not shown). The totalizer is then disengaged from the actuator racks before said racks start their final movement forward, which clears said totalizer and positions the printing segments 98 60 in accordance with the amount on said totalizer wheels. A sub-total operation is the same as a total operation with this exception; the totalizer wheels 108 after having been returned to zero, to properly position the printing segments, remain 65 in mesh with the racks 91 and the return movement forward of said racks rotates the totalizer wheels 108 back to their original positions, thus preserving the total.

Totalizer controlling mechanism

In former Ellis machines having four totalizers, the adding function of each totalizer was with few exceptions controlled by the traveling carriage in its tabulated positions by means of stops 75

coacting with hanging bar levers. These stops were arranged as desired along a tabulating stop bar carried by the traveling carriage. Also in former four-totalizer or quadruplex machines the subtractive feature of the No. 1 totalizer could be controlled either by stops on the traveling carriage cooperating with hanging bar levers, or by means of a subtract key. The starting bar of these former four-total machines was normally locked against depression and could be released either by means of stops arranged on the traveling carriage coacting with a hanging bar lever or by means of the different control keys. The machine of the instant invention while it is equipped with the same number of hanging bar levers as former quadruplex machines, the add hanging bar lever for the No. 1 totalizer is the only one used in conjunction with stops on the traveling carriage.

The traveling carriage of the instant machine has a tabulating stop 126 (Fig. 43), for each of its tabulated positions, spaced as desired along a tabulating stop bar 127 secured on the traveling carriage 64 (Fig. 16). These stops are arranged to cooperate with a No. 1 hanging bar lever 159 (Figs. 32, 33 and 43) to select the No. 1 totalizer for addition. However, the fact that subtract, non-add, sub-total and total operations supersede an add operation renders ineffective the No. 1 add selecting mechanism when the No. 1 totalizer is selected for any of the above operations. All other functions of the different totalizers are controlled by means of a row of control keys located at the extreme left of the keyboard. In 35 the detailed description to follow this controlling mechanism will be treated thoroughly.

Referring to Fig. 16, the upper ends of the control keys extend through slots in a keyboard plate 128 while the lower ends thereof are inserted in slots in an angle plate 129 secured to the left frame 60.

Each control key has wound around its lower end a compression spring 130 tensioned to force said keys upward, causing shoulders thereon to contact the keyboard plate 128 to retain said keys in their normal positions. A non-add key 131 (Fig. 1) controls the non-add feature of all totalizers. However, this does not interfere with the selection of a totalizer for any other than an adding operation. The non-add key 131 is of standard construction as used in former Ellis machines. Therefore, only a brief description of this key and its mechanism will be given later on in this specification.

55 Deposit and check keys

A deposit key 132 (Figs. 1, 24 and 25) selects the No. 4 totalizer for addition and as the No. 1 totalizer is constantly selected for addition by means of stops 126 on the traveling carriage, deposits are added into both the No. 1 and No. 4 totalizers. The deposit key 132 has therein a notch 133 adapted to cooperate with a lug 134 on a latch 135 pivoted at 136 to the left machine frame 60. The latch 135 has an arm 137 connected by a link 138 to a No. 4 add hanging bar lever 139. The No. 4 lever 139 (Figs. 24, 32 and 33) is connected by a hanging bar 140 to a No. 4 add controlling latch 141 pivoted on a stationary stud in a sub-frame 131 (Fig. 34). The rear arm of the latch 141 is arranged to cooperate with a projection on a No. 4 controlling crank 142 pivoted at 143 to the sub-frame 131.

A check key 144 (Figs. 1, 24 and 25) is arranged 75 to select the No. 1 totalizer for subtraction and

simultaneously select the No. 3 totalizer for addition. The check key 144 has therein a notch 158 arranged to cooperate with a lug 145 on a latch 146 pivoted on a stud 147 secured in the left frame 60. The latch 146 has an arm 148 connected by a link 149 to a No. 3 add hanging bar lever 150. The hanging bar levers 139 and 150 are pivoted on a stud 151 (Fig. 32) secured in a tabulating frame 152 supported between the main frames 60 and 61. The lever 150 (Figs. 24, 32 10 and 33) is connected by a hanging bar 153 to a No. 3 add controlling latch 154 pivoted at 155 to the sub-frame 131. A rear arm of the latch 154 is adapted to cooperate with a No. 3 add control crank 155 pivoted at 156 to the sub-frame. 15

Referring to Figs. 16 and 24, secured on the main shaft 69 is a No. 3 and No. 4 totalizer operating plate 156, which is oscillated through an angle of approximately 60 degrees each time the machine is operated, first movement clockwise, as 20 viewed in Figs. 16 and 24. Pivoted on the plate 156 is a No. 3 flying lever 157 and a No. 4 flying lever 160. The flying lever 157 is connected by a link 161 to a totalizer engaging arm 162 (Fig. 16) secured to an engaging shaft 159, journaled 25 in a No. 3 and No. 4 totalizer frame 163, connected by a pair of plates 164 and 165 to a No. 1 and No. 2 totalizer frame 166, which is in turn secured to the main frames 60 and 61.

The No. 4 flying lever 160 is connected by a 30 link 167 to a totalizer engaging crank 168 fast on an engaging shaft 169 journaled in the totalizer frame 163. Pivoted respectively on the flying levers 157 and 160 are pawls 170 and 171 urged counter-clockwise against stop studs secured in the levers 157 and 160 by springs 172 and 173. An upper arm of the pawl 170 is arranged to cooperate with a stud 174 in a No. 3 engaging crank 155 and a like arm on the pawl 171 cooperates with a stud 175 in the No. 4 engaging 40 crank 142. A lower arm of the pawl 170 is adapted to be engaged by a square stud 176 secured in the operating plate 156 and a lower arm of the pawl 171 is arranged to be engaged by a square stud 177 also fast in the plate 156. Directing attention to Fig. 16, secured in the frame 60 is a stud 178 having pivoted thereon a lever 179 which has an ear 180 adapted to be engaged by a nose 181 on the operating plate 156. Pivoted on an upper arm of the lever 179 is a pitman 182, its upper end being bifurcated to embrace the stud 174 in the engaging crank 155 and having a lug 183 which cooperates with the stud 175 in the crank 142.

Depression of the deposit key 132 (Fig. 24) 55 places the notch 133 opposite the lug 134 and the latch 135 is rocked clockwise by means of a spring 184 causing said lug to enter said notch to retain the key 132 depressed. Clockwise rocking of the latch 135 through the link 138, lever 139 and bar 140 rocks the No. 4 add controlling latch 141 counter-clockwise out of the path of the projection on the No. 4 engaging crank 142. Initial movement clockwise of the operating plate 156 (Figs. 16 and 24) removes the nose 181 from 60 engagement with the lever 179, allowing the crank 142 under tension of a spring 185 to rock counter-clockwise so that the stud 175 will not engage the add pawl 171. This allows the lower end of said pawl 171 to be engaged by the square stud 177 as the operating plate 156 continues 65 its clockwise movement thus causing the flying lever 160 to stop turning on its pivot and travel as a unit with the operating plate 156. This 70 through the link 167 rocks the engaging arm 168 75

for the No. 4 totalizer, causing the No. 4 totalizer wheels 108 (Fig. 3) to be properly meshed with the actuator racks 91, after said racks have been properly positioned for addition as described earlier herein. Final movement forward of the racks 91 actuates the totalizer wheels 108 commensurate with the amount set up on the keyboard after which the return movement of the operating plate 156 causes a stud 186 thereon to engage the flying lever 160 to rock the No. 4 engaging arm 168 counter-clockwise to disengage the totalizer wheels 108 from the racks 91.

Depression of the check key 144 (Fig. 24) causes the latch 146 under tension of a spring 187 to rock clockwise to move the latch 146 counter-clockwise to free the No. 3 engaging crank 155 so that the pawl 170 will engage the stud 176 to rock the arm 162 and shaft 155 counter-clockwise to properly engage the No. 3 totalizer wheels 108 with the racks 91 for addition in the same manner as described for the No. 4 totalizer. The No. 3 totalizer is disengaged from the racks near the end of an adding operation by means of a stud 190 carried by the operating plate 156 engaging the flying lever 157 during the return or home-ward movement of said operating plate 156. Near the end of the return movement of the operating plate 156 (Fig. 16) the nose 181 engages and rocks the lever 179 clockwise to restore the totalizer engaging cranks 142 and 155 to their normal positions.

The check and deposit keys are stay-down keys, that is, they are not automatically released after each machine operation but remain depressed. In order to prevent simultaneous depression of the check and deposit keys, these keys have been arranged so that depression of one releases the other. This mechanism is well illustrated in Figs. 23, 24 and 25, and will now be explained. The deposit key 132 has secured thereto a plate 191 which carries a stud 192 adapted to cooperate with the top edge of the latch 146 in a manner to be later described. Secured in the left frame 60 is a screw stud 193 upon which is pivoted a plate 194 bifurcated to embrace a stud 195 fast in the check key 144. The plate 194 carries a stud 196 arranged to cooperate with a projection 197 of the latch 135.

For example, let us assume that the check key 144 has been depressed, causing the latch 146 to be rocked clockwise. Depression of the deposit key 132 (Fig. 25) causes the stud 192 to engage and rock the latch 146 counter-clockwise to release the check key 144 which is then returned home by its spring 130. Likewise depression of the deposit key 132 causes the latch 135 to rock clockwise. Subsequent depression of the check key 144 by means of the stud 195 rocks the plate 194 clockwise, causing the stud 196 to engage the projection 197 to rock the latch 135 counter-clockwise, releasing the deposit key 132 which is returned home by its spring 130.

In addition to selecting the No. 3 totalizer for addition the check key 144 also selects the No. 1 totalizer for subtraction in the following manner:

The projection 188 (Fig. 25) of the latch 146 is arranged to engage a stud 199 in a lever 200 pivoted on the stud 147. The lever 200 carries a roller 201 arranged to cooperate with a No. 1 subtract cam 202 (Fig. 29) pivoted on a stud 203 secured in the left frame 60. The cam 202 is flexibly connected to a pawl 204 which is also pivoted on the stud 203 and has its rear end shaped to cooperate with the lower end of a No. 1 flying lever 205 pivoted at 206 to a No. 1 and No. 2

totalizer operating plate 207 carried by the shaft 69. The plate 207 is connected to the No. 3 and No. 4 operating plate 156 (Fig. 36) by means of the stud 190. The cam 202 (Fig. 29) has flexibly mounted thereon a pawl 208 also arranged to cooperate with the flying lever 205. The flying lever 205 is connected by a link 209 to a stud 210 in a No. 1 engaging arm 211 secured to an engaging shaft 212 journaled in the No. 1 and No. 2 totalizer frame 166 (Fig. 16). The lever 200 (Fig. 10 29) is connected by a link 213 to a lever 214 pivoted at 215 to the left frame 60. The lever 214 carries a stud 216 arranged to cooperate with the lower edge of a subtract transfer shifting pawl 217 having a hook 218 arranged to cooperate with the stud 210 for the purpose of shifting the No. 1 totalizer transfer mechanism from adding position to subtracting position.

Depression of the check key 144 (Fig. 25) rocks the latch 146 clockwise, which through the projection 198 and the stud 199 also rocks the lever 200 clockwise, causing the roller 201 to engage and rock the subtract cam 202 (Fig. 29) and the pawl 204 clockwise, thus placing the pawls 204 and 208 in the path of the flying lever 205. The 25 clockwise rocking of the lever 200 caused by depressing the check key 144, through the link 213 moves the lever 214 counter-clockwise, allowing the lowering of the pawl 217 to position its hook 218 into the path of the stud 210. Initial movement clockwise of the operating plate 207, which oscillates in unison with the No. 3 and No. 4 operating plate 156, causes the lower end of the No. 1 flying lever 205 to engage the pawl 204 to rock the arm 211 and shaft 212 counter-clockwise to properly mesh the No. 1 totalizer wheels 108 with the racks 91 for a subtract operation. Counter-clockwise movement of the arm 211 causes the stud 210 to engage the hook 218 to move the pawl 217 forwardly to shift the transfer 40 mechanism from add to subtract position. Return movement of the operating plate 207 causes the flying lever 205 to engage the pawl 208 to properly disengage the No. 1 totalizer from the racks 91 in subtract operation.

As above mentioned, the No. 1 totalizer is selected by the carriage for adding operation. The mechanism for accomplishing such selection is hereinafter described. However, it is desired to call attention to the fact that the subtract control of the No. 1 totalizer by the check key 144 supersedes the add control by the carriage.

Check key ribbon shifting mechanism

Depression of the check key 144 and the consequential clockwise rocking of the latch 146 also shifts the ribbon vibrating mechanism so that subtractive or debit items will be printed in a distinctive color. A link 219 (Fig. 31) connects the latch 146 and an arm 220 secured to the right end of a color shifting shaft 223 journaled in a top frame 224 (Fig. 16) supported between the main frames 60 and 61. Secured to the shaft 223 (Fig. 31) is a settable collar 225 having fast thereon a spring 226, the upper end of which is formed to cooperate with a slot in a link 227 pivoted to a color shift arm 228. The color shift arm has opposed notches 229 and 230 adapted to cooperate respectively with studs 231 and 232 in an arm of a yoke 233 pivotally mounted by means of trunnions secured in the top frame 224. The upper end of the color shift arm 228 is pivoted to a shifting lever 234 rotatably mounted on a bracket 235 secured to the top frame 224. The forward end of the lever 234 carries a stud 236 ar-

ranged to cooperate with two bifurcated ears on a ribbon shifting fork 237 mounted to slide vertically in the printer frame.

Depression of the check key 144 and consequential rocking of the latch 148, through the link 219 rocks the shaft 223 and the spring 226 counter-clockwise (Fig. 31) to shift the arm 228 so that the slot 229 will embrace the stud 231 to increase the leverage of the arm of the yoke 223. Subsequent rocking of the yoke, by the usual mechanism not here shown, lifts the ribbon fork 237 to a position where the lower or red portion of a bichrome ribbon will be interposed between the printing segments and the platen roll 65 to print subtract items in a distinctive color. When the check key 144 is released a spring 240 returns the arm 228 to its home position where the slot 230 embraces the stud 232 so that the upper or black portion of the bichrome ribbon will be interposed between the printing segments and the platen 65 during normal machine operations. Means have also been provided for automatically shifting the ribbon mechanism so that overdrafts will be printed in a distinctive color also. Such mechanism is fully described in the co-pending application of Chas. L. Lee, Ser. #605,160 filed April 14, 1932 and therefore will not be treated herein.

Deposit and check key locking mechanism

Means have been provided for preventing the release of either the check or deposit key after the starting bar 66 has been depressed. This mechanism likewise prevents depression of either of these keys after said starting bar has been depressed. Such mechanism will now be explained. Directing attention to Fig. 26, the deposit key 132 and the check key 144 carry respectively near their lower ends studs 241 and 242 arranged to cooperate respectively with hooks 243 and 244 on a detent 245 mounted to slide horizontally by means of two slots therein embracing a pair of shouldered screws 246 and 247 secured in the left frame 60. The detent 245 carries a stud 248 which extends through a slot in a projection 249 on a link 250 the rear end of which is connected to a lever 251, the purpose of which will be later described, pivoted on a screw 252 secured in the left frame 60. The forward end of the link 250 is pivoted to an arm 253 fast on the left end of a shaft 254 journaled in the main frames 60 and 61. Secured on the right end of the shaft 254 is an arm 255 bifurcated to embrace a stud 256 carried by a starting bar plate 257 pivoted at 260 to the right frame 61. The plate 257 is pivotally connected to a leg 261 of the starting bar 66.

Depression of the starting bar 66 rocks the plate 257 clockwise (Fig. 26), the arm 255, shaft 254 and arm 253 counter-clockwise forcing the link 250 and the detent 245 toward the front of the machine. The hooks 242 and 243 are arranged to slip over the studs 241 and 242, respectively when either the deposit or check key is depressed, and when the deposit or check keys are not depressed the hooks 242 and 243 pass under the studs 241 and 242. Thus depressing the starting bar 66, and the consequential forward movement of the detent 245 locks the deposit and check keys 132 and 144 against release when either of them is depressed, and locks either or both of said keys against depression.

Symbol printing mechanism

The totalizer control keys and the overdraft key are arranged so that upon depression they

position a symbol-printing segment relative to the particular transaction being made. For example, in add transactions the symbol-printing segment is positioned to print a plus sign, and so on. This mechanism is old, having been used in previous Ellis machines. Therefore it is thought that a brief description of said mechanism in connection with the deposit and check keys will be sufficient.

The lower end of the stem of the deposit and check keys 132 and 144 (Fig. 26) are arranged to cooperate with graduated camming lugs 262 and 263 carried by a symbol-selecting bar 264 reciprocably mounted on the screws 246 and 247. A link 265 connects the bar 264 with a crank 266 fast on the left end of a shaft 267 journaled in the frames 60 and 61. Secured on the right end of the shaft 267 is an arm 268 connected by a link 269 to another arm 270 pivoted at 271 to the printer frame. A link 272 pivotally connects the arm 270 and a symbol-printing segment 273 which is pivoted on one of the arms 99 (Fig. 2).

Depression of either the deposit or check key moves the bar 264 forward to rock the shaft 267 counter-clockwise to position the segment 273 in accordance with the transaction being made. Subsequent release of the printing segments, as explained hereinbefore causes the symbol to be printed opposite the row of figures it represents.

30

Add control for No. 1 and No. 2 totalizers

As brought out hereinbefore the No. 1 totalizer is selected for addition by the hanging bar lever 159 (Figs. 32 and 43) cooperating with the tabulating stops 126 arranged upon the tabulating stop bar 127 to agree with the columnar divisions of a ledger sheet 274. The hanging bar lever 159 (Fig. 32) is pivoted on the stud 151 as also is a No. 2 hanging bar lever 275. The levers 159 and 275 are respectively connected by hanging bars 276 and 277 (Fig. 35) to latches 280 and 281 pivoted on studs 282 and 283 secured in the main frame 60. The rear end of each of the latches 280 and 281 is shaped to cooperate respectively with notches in add engaging cranks 284 and 285 pivoted on studs 286 and 287 secured in the frame 60.

The engaging cranks 284 and 285 operate in exactly the same manner to condition the No. 1 and No. 2 totalizers for addition as the engaging cranks 155 and 142 (Fig. 33) do to condition the No. 3 and No. 4 totalizers for addition.

Referring to Figs. 29, 35 and 43, the clockwise rocking of the No. 1 add hanging bar lever 159 caused by it being engaged by one of the stops 126 rocks the latch 280 counter-clockwise. This allows the No. 1 engaging crank 284 to rock counter-clockwise under tension of a spring 288 so that a stud 289 in said crank 284 will move out of the path of a No. 1 add pawl 290 (Fig. 29) pivoted on the No. 1 flying lever 295 in order that the lower end of said pawl 290 will remain in the path of a stud 291 carried by the plate 207. Initial movement clockwise of the plate 207 causes the stud 291 to engage the pawl 290 to rock the No. 1 engaging arm 211 and shaft 212 counter-clockwise to properly engage the No. 1 totalizer with the actuator racks 91 for an adding operation. Return movement counter-clockwise of the plate 207 causes the stud 199 to engage the No. 1 flying lever 205 to disengage the No. 1 totalizer from the racks near the end of an adding operation.

The No. 2 totalizer is also selected for addition.

each time the No. 1 totalizer is cleared and the manner in which this is accomplished will be described later in this specification.

5   *Balance key for the No. 1 totalizer*

Included in the row of control keys is a balance key 292 (Figs. 1, 17 and 29) which is primarily a total key for the No. 1 totalizer. As it is desired in the present machine to preserve a total 10 of the balances, the key 292 is arranged to select the No. 2 totalizer for addition simultaneously with the selection of the No. 1 totalizer for total-taking. This mechanism will now be described.

Referring to Fig. 29, the key 292 has a notch 15 293 arranged to cooperate with a lug 294 on a No. 1 total latch 295 pivoted on a stud 296 secured in the left frame 60. The lower end of the latch 295 is arranged to cooperate with a stud 297 in a No. 1 total latch lever 298 also pivoted on the stud 20 296 and having therein a stud 299 adapted to cooperate with a No. 1 total cam lever 300 pivoted on the stud 203. The rear end of the lever 300 cooperates with a stud 301 fast in the cam 202.

Depression of the balance key 292 (Fig. 29) 25 allows the latch 295 and the lever 298 to be rocked clockwise by a spring 302, causing the stud 299 to rock the lever 300 and cam 202 clockwise to place the pawls 204 and 208 in the path of the flying lever 205. Subsequent oscillation of the 30 plate 207 during machine operation causes the flying lever 205 to cooperate with the pawls 204 and 208 to engage and disengage the No. 1 totalizer with the actuator racks 91 for a total operation in exactly the same manner as for a subtract operation, which was described hereinbefore.

Calling attention to Fig. 17, the balance key 292 carries a stud 303 which cooperates with the forward end of a No. 2 add selecting lever 304 40 pivoted on a stud 305 carried by the left frame 60. The rear end of the lever 304 is connected to the lower end of the No. 2 hanging bar 277, which as previously stated connects the No. 2 hanging bar lever 275 to the No. 2 add latch 281. Secured 45 in the crank 285 is a stud 306 arranged to cooperate with a No. 2 add pawl 307 pivoted to a No. 2 flying lever 308 which is in turn pivoted on a stud 309 carried by the operating plate 207. A link 310 connects the flying lever 308 to a No. 2 50 engaging arm 311 secured to an engaging shaft 312 journaled in the totalizer frame 166.

Depression of the balance key 292 causes the stud 303 to rock the lever 304 clockwise, thus 55 rocking the latch 281 counter-clockwise out of the path of the engaging crank 285. Initial movement clockwise of the operating plate 207 first releases the engaging crank 285 to the action of a spring 313 (Fig. 35) which moves said crank counter-clockwise so that the stud 306 will not 60 be in the path of the pawl 307 (Fig. 17). This enables the lower end of the pawl 307 to be engaged by a stud 314 fast in the operating plate 207, as said plate continues its clockwise movement, to rock the arm 311 and shaft 312 clockwise to properly engage the No. 2 totalizer wheels 108 with the actuator racks 91 for an adding operation. Near the end of the return movement counter-clockwise of the plate 207 a stud 315 fast therein engages the flying lever 308 to rock the 65 arm 311 and shaft 312 counter-clockwise to disengage the No. 2 totalizer wheels from the racks 91 in an adding operation. From the above explanation it will be seen that each time a total is 70 taken of the No. 1 totalizer, this total is automatically added into the No. 2 totalizer.

Total balance key

As explained above, total balances are stored in the No. 2 totalizer. Means for printing a total of the No. 2 totalizer is provided and will now be explained. Referring to Figs. 1 and 17, a total balance key 316 has a notch 317 which cooperates with a lug 318 on a No. 2 total latch 319 pivoted on a stud 320 secured in the frame 60. Fast in the latch 319 is a stud 321 adapted to cooperate with a No. 2 total cam lever 322 pivoted on a stud 323 carried by the left frame 60. The cam lever 322 is flexibly connected to a pawl 324 also pivoted on the stud 323 and having flexibly mounted thereon a pawl 325.

Depression of the total balance key 316 allows the lug 318 to enter the notch 317 as the latch 319 is rocked clockwise by a spring 326, whereupon the stud 321 rocks the cam lever 322 clockwise and moves the pawls 324 and 325 into the path of the flying lever 308. Initial movement clockwise of the operating plate 207 during machine operation causes the flying lever 308 to first engage the pawl 324 to rock the arm 311 and shaft 312 clockwise to properly engage the No. 2 totalizer wheels 108 with the actuator racks 91 for a total-taking operation. The final movement counter-clockwise of the operating plate 207 causes the flying lever 308 to operatively engage the pawl 325 to disengage the totalizer wheels from the racks 3 after said totalizer has been returned to zero thereby.

Total deposit and total check keys

It will be recalled that deposit totals are stored in the No. 4 totalizer and check totals are stored in the No. 3 totalizer. Means for taking totals on these totalizers will now be explained. Calling attention to Fig. 30, a total check key 327 has a notch 330 which cooperates with a lug 331 on a No. 3 total latch 332 pivoted at 333 to the frame 60. Secured in the lower end of the latch 332 is a stud 334 which cooperates with a No. 3 total cam 335 pivoted on the stud 203 and flexibly connected to a No. 3 total cam lever 336 also pivoted on the stud 203. Flexibly mounted on the lever 336 is a pair of pawls 337 and 338 arranged to cooperate with the lower end of the No. 3 flying lever 157.

Depression of the total key 327 allows the latch 332 to be rocked clockwise by a spring 339 causing the stud 334 to rock the cam 335 and the lever 336 clockwise, thus placing the pawls 337 and 338 in the path of the flying lever 157. Subsequent oscillation of the operating plate 156 causes the No. 3 totalizer to be engaged with and disengaged from the actuator racks 91 in exactly the same manner as the No. 1 totalizer is engaged with and disengaged from the racks as previously described.

Directing attention to Fig. 16, a total deposit key 340 has a notch 341 arranged to cooperate with a lug 342 on a No. 4 total latch 343 pivoted at 344 to the left frame 60. A link 345 connects the latch 343 to a lever 346 pivoted on the stud 320 and carrying a stud 347 which cooperates with a No. 4 total cam 350 pivoted on the stud 323. The cam 350 is flexibly connected to a No. 4 pawl lever 351 also pivoted on the stud 323 and having mounted thereon a by pass pawl 352. The pawl lever 351 and the pawl 352 are arranged to cooperate with the flying lever 160.

Depression of the total check key 340 allows the latch 343 and the lever 346 to be rocked clockwise by a spring 353 causing the stud 347 to

rock the cam 350 and the pawl lever 351 clockwise to place the pawl lever 351 and the by pass pawl 352 in the path of the flying lever 160. Subsequent oscillation of the plate 156 causes the No. 5 4 totalizer to be engaged with and disengaged from the actuator racks 91 in the same manner as previously described for the No. 2 totalizer.

Releasing mechanism for the control keys

10 Figs. 36, 37 and 38 are views illustrating the assembled releasing mechanism for the control keys. Considerable change was required in this releasing mechanism in order to adapt it for use in the machine of the instant invention. The 15 releasing mechanism will now be explained.

Total key releasing mechanism

Secured in the left frame 60 is a stud 354 (Fig. 38) having pivoted thereon a lever 355 which 20 carries a stud 356 embraced by the bifurcated forward end of a total release bar 357 having near its rear end a slot 358 through which extends a stud 359 fast in a sub-total release lever 360 pivoted at 361 to the frame 60. Pivoted on 25 the bar 357 is a total releasing by pass pawl 362 retained in neutral position by a spring 363 tensioned between said pawl and the bar 357. The upper end of the pawl 362 is notched to cooperate with a stud 364 secured in the frame 60 30 and the lower end of said pawl 362 is shaped to coact with a stud 348 carried by the operating plate 207. The bar 357 has a plurality of projections 365 arranged to cooperate with the lugs on the total key latches. There is a projection 365 for each of the following latches: Latch 319 for the total balance key 316 (Fig. 17); latch 343 for the total deposit key 340 (Fig. 16); latch 332 for the total check key 327 (Fig. 30); and latch 295 for the No. 1 balance key 292 (Fig. 29). 40 A spring 366 (Fig. 38) is tensioned to normally retain the projections 365 in contact with the lugs of the different latches. The bar 357 has an extension 367, the rear edge of which is arranged to cooperate with a finger 368 on a non-add key latch 426 (Figs. 34 and 35). The forward edge of the extension 367 coacts with a stud 370 fast in an arm 371 secured to the left end of a shaft 372 journaled in the frames 60 and 61. Secured to the righthand end of the 50 shaft 372 is an arm 373 (Fig. 48) bifurcated to embrace a stud 374 secured in a starting bar lock plate 375 pivoted on a stud 376 in the right frame 61. The shaft 372 has secured thereon an arm 377 connected by a rod 380 to a starting bar release lever 381 pivoted on the stud 151 (Fig. 32). The starting bar release lever 381 is arranged to cooperate with stops on the traveling carriage for the purpose of unlocking the starting bar in tabulated position of said traveling carriage. The locking plate 375 (Fig. 48) has a shoulder 382 held normally in the path of a stud 383 in the starting bar plate 257 by a spring 384 which is connected to the arm 373. This results in the starting bar 66 being normally 60 locked against depression.

In describing how the total key releasing mechanism functions the total check key 327 (Figs. 30 and 38) will be used as a representative of all the total keys and also the non-add key 70 131, as all these keys are released at the same time and in a similar manner. Calling attention to Fig. 38, depression of the total check key 327 allows the lug 331 to be moved into the notch 330 by the spring 339. The lug 331 co-acting with the projection 365 shifts the bar

357 forwardly flexing the spring 366. Initial movement clockwise of the operating plate 207 causes the stud 348 to wipe past the lower end of the pawl 362. On the return movement of the plate 207 the stud 348 engages the lower 5 end of the by pass pawl 362 rocking it clockwise on its pivot until the notched upper end thereof contacts the stud 364. Continued movement of the plate 207 causes the bar 357 to be moved rearwardly, rocking the latch 332 counter-clockwise to force the lug 331 out of the notch 330. The key 327 is then restored to normal position by its spring 130. The stud 348 passes beyond the plane of the pawl 362 immediately after the key 327 has been restored, thus leaving the lug 15 331 resting against the edge of said key 327. This counter-clockwise movement of the latch 332 allows the cam 335 (Fig. 30) and the pawls 337 and 338 to rotate counter-clockwise under their own weight until said pawls 337 and 338 are 20 out of the path of the flying lever 157.

Depression of the key 327 (Fig. 38) and the consequential shifting of the bar 357 causes the extension 367 to rock the arm 371 and shaft 372 clockwise, as viewed in Fig. 38 and counter-clockwise as viewed in Fig. 48. This rocks the latch plate 375 clockwise (Fig. 48) to a position where the shoulder 382 will be out of the path of the stud 383 so that the starting bar 66 may 30 be depressed.

The depressed total keys and the non-add key may, if desired, be released manually by means of an error key 385 (Figs. 1 and 38) which carries a roller 386 arranged to cooperate with a foot 387 on the lever 355. Depression of the error key 385 causes the roller 386 to engage and rock the lever 355 clockwise to shift the bar 357 rearwardly to force the lug 331 out of the notch 330, thereby releasing the key 327. The error key 385 has no latch consequently never remains 40 depressed but is always returned to its upward position by its spring 130. Releasing of the total and non-add keys by shifting the bar 357 rearwardly, either manually or automatically, as described above, allows the starting bar lock plate 45 375 (Fig. 48) to be returned to its effective position by the spring 384.

Sub-total mechanism

In total operations the totalizer wheels 108 50 after being engaged with the actuator racks 91 are first returned to zero, which positions the printing segments 98 commensurate with the amount on said totalizer. While standing at zero the totalizer wheels 108 are disengaged from 55 the racks thus leaving the totalizer clear. In sub-total operations the totalizer wheels 108 remain in mesh with the actuator racks 91 after being returned to zero, so that the return movement of said racks will replace the total within 60 said totalizer. This is accomplished, for instance, in the No. 3 totalizer (Fig. 30) by restoring the latch 332 during the first cycle of operation which releases the total check key 327 and allows the pawl 338 to move counter-clockwise out of the 65 path of the flying lever 157. In total operations the latch 332 remains in effective position until near the end of machine operation, which allows the pawl 338 to remain in the path of the flying lever 157 causing the totalizer to be disengaged 70 from the actuator while standing at zero.

A sub-total key has been provided for use in connection with any of the total keys for the purpose of sub-totalizing the different totalizers. The sub-total key is also used to release the start- 75

ing bar when adding an old balance into the No. 1 totalizer and again the sub-total key may be used to release either the check or deposit keys and simultaneously release the starting bar so that the machine may be operated. The sub-total key and its mechanism will now be explained.

Reciprocably mounted just back of the release bar 357 (Figs. 28 and 36) is a sub-total release bar 388 bifurcated on one end to embrace the stud 356 carried by the lever 355 and having its other end pivoted on the stud 359 carried by the lever 360. The total release bar 357 and the sub-total release bar 388 carry respectively studs 389 and 390 having interposed between them a wedge 391 pivoted to a sub-total key 392 (Fig. 38) mounted to slide vertically by having its upper end extending through a slot in a plate 393 secured to the keyboard plate 128 and its lower end extending through a slot in a bracket 394 secured to the angle 129. The key 392 has in its lower end a screw 395 arranged to be normally held in contact with the bracket 394 by its spring 130. The sub-total key 392 has a notch 396 arranged to cooperate with a lug 397 on a sub-total latch 400 pivoted on a stud 401 carried by the left frame 60. The latch 400 is adapted to cooperate with a stud 402 secured in the total release bar 357. The wedge 391 is undercut in such a manner that it does not interfere in any way with the movement of the total release bar when the sub-total key is not depressed.

As an example, let us assume it is desired to sub-totalize the No. 3 or total check totalizer. The total check key 327 (Fig. 38) is first depressed, as for a total operation, causing the lug 331 to enter the notch 330, to move the bar 357 forwardly. Next the sub-total key 392 is depressed, forcing the upper end of the wedge 391 between the studs 389 and 390, and allowing the lug 397 to enter the notch 396 when the latch 400 is rocked clockwise by a spring 403. Initial movement clockwise of the operating plate 207 causes a stud 404 carried thereby to engage and rock the lever 360 counter-clockwise to shift the sub-total release bar 388 rearwardly, which through the studs 389 and 390 and the wedge 391 causes the total release bar 357 to shift in unison therewith to restore the latch 332 to release the key 327. This rocks the pawl 338 (Fig. 30) out of the path of the flying lever 157 so that the No. 3 totalizer will remain in mesh with the actuator racks 91 and the total will be reentered in said No. 3 totalizer. This rearward movement of the release bars 357 and 388 also causes the stud 402 to engage and restore the latch 400, thus releasing the sub-total key 392.

The sub-total key 392 is arranged to release the starting bar 66 in the following manner: Depression of the sub-total key 392 (Figs. 36 and 38) allows the latch 400 to move clockwise to engage the stud 402 to shift the total release bar 357 forwardly, causing the extension 361 to rock the shaft 372 counter-clockwise as observed in Fig. 48 to unlock the starting bar 66 in the manner previously described.

Release of the starting bar by the deposit and check keys

The machine of the instant invention is so arranged that depression of either the deposit key 132 or the check key 144 unlocks the starting bar 66 so that the machine may be operated. A description of this mechanism will now be given. A release bar 405 (Figs. 27 and 36) has in its

opposite ends slots 406 and 407. The slot 406 embraces the stud 359 carried by the lever 360 while the slot 407 embraces a stud 408 fast in the sub-total release bar 388. Thus the bar 405 is slidably mounted upon the sub-total release bar 388. The bar 405 has a pair of projections 409 and 410 arranged to cooperate respectively with the lugs 134 and 145 on the latches 135 and 146 for the deposit key 132 and the check key 144. The bar 405 also has an extension 411 which coacts with the stud 370 carried by the arm 371.

Depression of either the deposit key or the check key allows the latch for the key depressed to move forwardly (Fig. 38) under tension of its spring, to slide the bar 405 toward the front of the machine, thereby rocking the arm 371, shaft 372 and arm 373 counter-clockwise and the plate 375 clockwise, as viewed in Fig. 48 to unlock the starting bar 66. The release bar 405 is restored to normal position by the arm 371 under influence of the spring 384 when the deposit or check key is released.

Release of deposit and check keys by other control keys

Mechanism is provided for releasing the deposit key and the check key by the error key 385 and will now be described. Referring to Figs. 22, 36 and 38, adjacent the frame 60 is a release bar 412 the forward end of which is bifurcated to embrace the stud 356 carried by the lever 355. The rear end of the bar 412 is slotted to receive a stud 413 secured in the frame 60. The bar 412 has projections 414 and 415 which cooperate respectively with the lugs 134 and 145 on the latches 135 and 146 to release the deposit key 132 and the check key 144 when the release bar 412 is shifted rearwardly, caused by the roller 386 (Fig. 38) engaging and rocking the lever 355 clockwise when the error key 385 is depressed.

As previously stated, the deposit key 132 and the check key 144 are stay-down keys. The fact that the depression of either of these keys selects another totalizer into which the total checks or total deposits are stored makes it necessary that these keys be released when totalizing or sub-totalizing the No. 1 totalizer, to present such total or sub-total from being added into the storage totalizer for whichever of the above keys is depressed.

The stud 303 (Fig. 25) in the balance key 292 is adapted to cooperate with the forward arm of a two-armed lever 416 pivoted on the stud 305. The rear arm of the lever 416 is adapted to cooperate with the stud 199 in the latch lever 200. The rear arm of the lever 416 also carries a stud 417 which cooperates with the projection 197 on the latch 135. Secured to the sub-total key 392 is a plate 418 arranged to cooperate with a stud 419 in the forward arm of the lever 416.

Depression of either the balance key 292 or the sub-total key 392 by means of the stud 303 or the plate 418 rocks the lever 416 clockwise whereupon the stud 199 rocks the lever 200 and latch 146 counter-clockwise to release the check key 144; or in case the deposit key 132 is depressed, the stud 417 cooperating with the projection 197 restores the latch 135 thereby releasing said deposit key.

Repeat key mechanism

The repeat key mechanism used in the instant machine operates to disable the amount key releasing mechanism in exactly the same manner

as in former Ellis machines. This mechanism is fully explained in the Ellis patent No. 1,203,863, referred to at the beginning of this specification. However, the manner in which a repeat key 420 (Figs. 1, 16, 36 and 38) is released by the error key 385 has been slightly altered in the instant machine and will now be briefly described.

Depression of the repeat key 420 allows a lug 421 on a spring-pulled latch 422 to enter a notch 423 in said key. This clockwise movement of the latch 422 shifts the amount key release mechanism in the usual manner to a position where it is ineffective, thus causing said amount keys to remain depressed after machine operation in order to duplicate the previous transaction.

Depression of the error key 385 through the lever 355 causes a projection 424 (Fig. 22) on the release bar 412 to engage the lug 421 and rock the latch 422 counter-clockwise to release the repeat key 420 and its mechanism for restoration to normal position.

Non-add mechanism

The non-add mechanism, which is well illustrated in Figs. 33, 34 and 35 is the same as that used in previous Ellis machines. Therefore it is thought that a brief description of this mechanism will be sufficient. The left frame 60 (Figs. 34 and 35) carries a stud 425 upon which is pivoted the No. 1 and No. 2 non-add latch 426, having a formed projection 427 with the finger 368 arranged to cooperate with a notch 430 in the non-add key 131. The latch 426 has a shoulder 432 and a tail 433 arranged to cooperate respectively with lugs 434 and 435 on the engaging cranks 284 and 285. The projection 427 carries a stud 436 which cooperates with a slot in an arm 437 (Figs. 33 and 34) of a No. 3 and No. 4 non-add lever 438 pivoted at 439 to the sub-frame 131. The lever 438 has a shoulder 440 and a tail 441 arranged to cooperate respectively with lugs 442 and 443 on the engaging cranks 155 and 142.

Depression of the non-add key 131 allows the finger 368 to enter the notch 430 as the latch 426 and lever 438 are rocked clockwise by a spring 444 (Fig. 33). This causes the shoulder 432 and the tail 433 to move into the paths of the lugs 434 and 435, thus blocking the counter-clockwise movement of the cranks 284 and 285, which renders ineffective the No. 1 and No. 2 totalizer engaging mechanism for add operations. In a like manner, the clockwise rocking of the lever 438 caused also by depressing the non-add key 131 moves the shoulder 440 and tail 441 into the paths of the lugs 442 and 443 to block the movement of the cranks 155 and 142 thereby making ineffective the add engaging mechanism for the Nos. 3 and 4 totalizers.

The manner in which the non-add key 131 is released and its mechanism restored both automatically and manually was explained hereinbefore when a description was given of the control key releasing mechanism.

Automatic overdraft mechanism

When an overdraft occurs in an individual's account, the balance key 292 (Fig. 16) is automatically locked against depression, which is a signal to the operator that such overdraft has occurred. Of course, if an amount sufficient to overbalance the overdraft is subsequently added into the No. 1 totalizer the balance key is automatically unlocked. If in attempting to balance

a certain account the operator finds the balance key 292 locked, it then becomes necessary to make an overdraft operation which is entirely automatic, it being necessary only for the operator to depress an overdraft key 445 (Figs. 2 and 39), 5 provided neither of the keys 132 nor 144 are still depressed. In case either of said keys 132 or 144 is depressed, then as will be hereinafter described in detail, it is necessary to release such depressed key before the overdraft key 445 can 10 be depressed.

Depression of the overdraft key 445 causes the machine to operate through the three cycles necessary to transpose a complementary overdraft to a positive amount. Broadly, the method 15 of transposing and printing the positive amount of the overdraft is as follows:

When an overdraft occurs the complement of said overdraft remains in No. 1 totalizer. During the first cycle of an overdraft operation the No. 20 1 totalizer is cleared and the complement of the overdraft simultaneously added into an auxiliary overdraft differential. In the second cycle of an overdraft operation the complement is subtracted from the cleared No. 1 totalizer and in the instant 25 machine such complement is also simultaneously added into the total balance or No. 2 totalizer, which is the same as subtracting the positive amount of the overdraft from said No. 2 totalizer. The subtracting of the complementary overdraft 30 from the cleared No. 1 totalizer results in the positive amount of said overdraft being set up in the No. 1 totalizer. In the third cycle of an overdraft operation the No. 1 totalizer is again cleared and the positive amount of the overdraft 35 printed upon the tally web and ledger sheet in a distinctive color.

During the first and second cycles of an overdraft operation the printing, the tally feed and the platen feed mechanisms are disabled, thus 40 preventing the printing of the complementary overdraft and the unnecessary feeding of the tally web and ledger sheet.

Basically the automatic overdraft mechanism used in the instant machine is exactly the same as that illustrated and described in the copending application for Letters Patent of Charles L. Lee, Serial No. 605,160 filed April 14, 1932, with the following exceptions:

The finger-piece of the overdraft key of the instant machine is flexibly coupled to the operating portion of said overdraft key, to the end that if through mistake or accident the operator holds the finger-piece depressed after completion of an overdraft operation such finger-piece will be automatically disconnected from the operating portion of the overdraft key, which is then free to be restored to its normal position independent of said finger-piece. When the finger-piece is released it is spring-restored to normal position and again effectively coupled to the operating portion of the overdraft key. Other exceptions are changes in the method of selecting the No. 1 totalizer for subtraction in the second cycle of an overdraft operation and the manner in which the symbol-printing segment is positioned in the third cycle of an overdraft operation.

In the instant machine an interlock has been provided between the deposit key 136, the check key 144 and the overdraft key 445 so that the overdraft key will be locked against depression as long as either of the above keys remain depressed. Inasmuch as the automatic overdraft mechanism has been thoroughly explained in the patent application of Lee referred to above, only that part

of said mechanism which is pertinent to the instant invention will be treated in the succeeding description.

Referring to Figs. 39, 40 and 41, the overdraft key 445 is composed principally of two parts—a stem 446 and an operating pitman 447 slidably connected to each other by means of slots 450 and 451 in the pitman 447 through one of which (450) extends a headed stud 452 secured in the stem 446. Another headed stud 453 extends through the slot 451 and a clearance hole in the stem 446, and is secured in an overdraft key latch 454 having a bent lug 455 arranged to cooperate with a notch 456 in the pitman 447. A spring 457 is tensioned to normally hold the lug 455 in the notch 456. The latch 454 has an extension 458 arranged to cooperate with a stud 459 in a detent 460 pivoted at 461 to the right frame 61. The detent 460 is connected by a link 462 to a detent release cam arm 448 (Fig. 2) which is oscillated near the end of an overdraft operation. The overdraft key 445 (Figs. 39 and 40) is slidably mounted in the frame 61 by means of a slotted plate 463 secured to the said frame through which extends the stem 446, and by means of a stud 464 fast in the frame 61, which cooperates with the bifurcated lower end of the pitman 447. A spring 465 is tensioned to normally retain the overdraft key in its upward position.

Depression of the overdraft key 445 (Fig. 40) allows a hook 466 on the detent 460 to latch over a lug 467 on the pitman 447 to retain the overdraft key depressed. Depression of the overdraft key also places the extension 458 in the path of the stud 459. Normally the overdraft key 445 is restored as a unit by the spring 465 when the hook 466 is disengaged from the lug 467 by the counterclockwise movement of the detent 460 near the end of an overdraft operation, the stud 459 passing idly below the extension 458. If through accident or mistake the overdraft key were held in its depressed position after the completion of a machine operation, the stud 459 would then engage the extension 458 rocking the latch 454 counter-clockwise, thereby disconnecting the stem 446 from the pitman 447. This allows the pitman 447 to be restored to its upward position by the spring 465 independent of the stem 446, which when released is returned upward by the spring 457 until the lug 455 reengages the notch 456.

Interlock between deposit and check keys and the overdraft key

The deposit key 132 (Figs. 39, 40 and 41) and the check key 144 carry respectively studs 468 and 469 arranged to cooperate with an arm 470 pivoted to the left frame 60 and bifurcated to receive a stud 471 in an arm 472 secured to the left end of a shaft 473 journaled in the frames 60 and 61. Secured to the right end of the shaft 473 is arm 474 connected by a link 475 to a locking pawl 476 pivoted at 477 to the right frame 61. The pawl 476 has a notch 480 adapted to cooperate with an extension 481 of the pitman 477.

Depression of the deposit key 132 or the check key 144 causes the respective stud 468 or 469 to engage and rock the arm 470 counter-clockwise to rock the shaft 473 and the pawl 476 clockwise against the tension of a spring 482. This causes the notch 480 to pass under the extension 481 to block the movement of the overdraft key 445 when either the deposit key 132 or the check key 144 is depressed.

The pitman 447 has pivoted thereto a link 483 (Fig. 40) having a slot through which extends a stud 484 secured in one arm of a multi-armed lever 485 pivoted on a stud 486 fast in the frame 61. Another arm of the lever 485 is bifurcated to embrace a stud 487 carried by the starting bar plate 251. Through the above train of mechanism depression of the overdraft key 445 rocks the plate 251 counter-clockwise (Fig. 40) to release the machine for an overdraft operation.

Due to the interlock between the overdraft key and the deposit and check keys it is necessary that the latter keys be released in order that the overdraft key may be depressed. The sub-total key 392 (Fig. 38) furnishes a convenient means for accomplishing this purpose, as it not only releases either the deposit key 132 or check key 144 but in addition unlocks the starting bar plate 251 (Fig. 48) by rocking the latch plate 375 away from the stud 383 as explained hereinbefore, this latter step is obviously necessary before it is possible to depress the overdraft key 445.

Calling attention to Fig. 29, journaled in the frames 60 and 61 is an overdraft control shaft 636 having secured thereto a Y-shaped arm 637 arranged to cooperate with a stud 638 carried by the No. 1 total latch lever 298. Secured in the arm 637 is a stud 639 adapted to cooperate with a cam slot 640 and a No. 1 subtract operating lever 641 loosely mounted on the stud 296. The lever 641 (Fig. 17) carries a stud 642 which cooperates with a projection 643 on the No. 2 add selecting lever 304. The stud 639 carried by the arm 637 is also arranged to cooperate with a cam slot 644 (Fig. 16) in an arm 645 pivoted on the stud 296 and whose lower end is adapted to cooperate with a stud 646 in the symbol selecting bar 264.

Depression of the overdraft key 445 (Fig. 39) releases the shaft 636 (Fig. 29) to the action of a spring 650 (Fig. 2), attached to the frame 61 and to an arm 651 secured to the shaft 636. The arm 651 is connected to an arm 652 by a link 653. The method of releasing the arm 652 to rock shaft 636 is fully illustrated and described in the above named Lee application. When released, the spring 650 forces the shaft 636 counter-clockwise to rock the lever 298 clockwise, by means of the arm 637 and stud 638, to select the No. 1 totalizer for totaling as previously explained. During the second cycle of an overdraft operation the shaft 636 (Fig. 29) is rocked clockwise by mechanism not here shown, and through the stud 639 and cam slot 640 forces the lever 641 counter-clockwise, causing a nose 647 thereon to engage a stud 648 in the subtract lever 200 to rock said lever clockwise to condition the No. 1 totalizer for a subtract operation as described hereinbefore. In the third cycle of an overdraft operation the shaft 636 and the arm 637 are again rocked counter-clockwise to condition the No. 1 totalizer for another total operation in the same manner as in the first cycle of an overdraft operation. At this time the stud 639 (Fig. 16) through the cam slot 644 rocks the arm 645 counter-clockwise to force the symbol selecting bar 264 (Fig. 16) forwardly to properly position the symbol printing segment 273. Near the end of an overdraft operation the shaft 636 and the cam 637 are returned to normal position as shown in Fig. 29.

Reflex ribbon mechanism

The machine in which the instant invention is incorporated is provided with a reflex inking de-

vice, (Fig. 7) arranged so that a double thickness of an inking ribbon 548 is interposed between the type and the platen roll. These two thicknesses of inking ribbon are spaced apart sufficiently to allow a web of tally paper to be threaded there-between and the thickness of ribbon nearest the platen 65 is properly spaced therefrom to allow a web of paper to be inserted between said ribbon and the platen. This arrangement of the inking ribbon 548 makes it possible, with a single impression or stroke of the printing type, to make original entries upon two separate webs of paper, one of which is wound around the platen 65 and the other fed between the folds of the reflexed ribbon, in a manner to be later described. This arrangement does not in any way interfere with the movement of the traveling carriage and the use of the platen roll for presenting different portions of the wide web of paper wound therearound to the printing type. While Fig. 7 is possibly self-explanatory, still the ribbon mechanism will be briefly described.

Mounted in close relation upon the machine case 63 (Fig. 7) is a pair of reversible ribbon spools 550 and 551 which are alternately revolved by the conventional Ellis ribbon feeding mechanism. Secured on the machine case 63 is a plate 552 having mounted thereon a roller 553 flanged at either end and of proper width between the flanges to receive the ink ribbon 548. The plate 552 also carries a pair of studs 554 to properly space the folds of the inking ribbon 548.

The ends of the one-piece ribbon 548 are first attached to the cores of the spools 550 and 551. Next the ribbon is threaded through the reversing arms for the respective spools. It is then carried around one of the studs 554, the flanged roller 553 and finally around the other stud 554 in the manner illustrated in Fig. 7. The double thickness of ribbon is then threaded through the times of the ribbon vibrating fork 231 (Fig. 31) so that it may be lifted into printing position thereby. The manner in which this reflex inking ribbon is employed to advantage in the instant machine will be related hereinafter.

Dating device

The instant machine is equipped with a dating device similar to that used on former Ellis machines. However, novel means have been provided for automatically locking the settable levers of the dating device against manipulation during machine operation. The dating and locking mechanism will now be explained.

Calling attention to Figs. 1, 5 and 6, secured to the left frame 60 is a dating frame composed of plates 488 and 489 held in parallel alignment by a plurality of shouldered studs upon one of which, 490, is pivoted three settable levers, namely a units of days lever 491, a tens of days lever 492 and a month lever 493. The upper ends of these levers form finger-pieces that extend through slots in an arc-shaped plate 494 secured in radial alignment with the stud 490 by means of slots in the plates 488 and 489. Each of the levers 491, 492 and 493 terminates in a segment having a plurality of notches 495 adapted to cooperate with a stud 496 in each of a plurality of spring-pulled locating levers 497 pivoted on a stud 500 extending between the plates 488 and 489. Secured in each of the levers 492, 491 and 493 is a stud 501 which cooperates with a projection 502 on each of a plurality of date actuator slides 503 mounted to reciprocate horizontally between the bars 92 and 93. Each slide

503 has a vertical slot 504 adapted to cooperate with studs 505 in arms 506 of a plurality of multi-armed reducing levers 507 pivoted on the shaft 74. Each of the reducing levers 507 is connected by a link 508 to a date printing segment 509, 5 one for the units of days, one for the tens of days, and one for the months. Each date printing segment 509 is pivoted on a printing arm 510 which functions exactly like the arms 99 (Fig. 3) described earlier in this specification. Each arm 10 506 (Fig. 5) terminates in a toothed sector 511, the tooth spaces of which are adapted to cooperate with the lining bar 95. The arms 506 also cooperate with the leading frame 88 in exactly the same manner as the amount reducing levers 15 55 (Fig. 3).

The plate 494 (Fig. 1) has engraved thereon opposite the respective levers 491, 492 and 493 numerals representing the units of days and tens of days, and abbreviations for the different 20 months. This engraving is spaced to correspond with the different positions of its respective date setting lever as determined by the notches 495 and the levers 497. Moving the date levers from one position to another causes the stud 496 under 25 spring tension to move out of and into the notches 495 to retain the date levers in the desired positions.

The present machine is provided with a year printing segment (not shown) which is positioned by being moved manually until the desired year is in printing position. The year segment is retained in position by a link similar to the link 508 having a stud which under spring tension cooperates with notches in a segment 35 (none of which are here shown). The above notches are spaced commensurate with the different printing positions of the year segment.

Means for locking the date levers 491, 492 and 493 against manipulation after the machine has 40 been released for operation are provided and will now be described. The previously mentioned lever 251 (Fig. 5) has a right angled extension 512 arranged to be rocked into the path of the levers 497 in the following manner:

Depression of the starting bar 66 rocks the plate 257 counter-clockwise, as observed in Fig. 5, which through the stud 256, arm 255, shaft 254, arm 253 and link 250 rocks the lever 251 clockwise, whereupon the extension 512 is moved into 50 the path of the levers 497, thereby locking the studs 496 in the selected notches 495 to prevent manipulation of the date setting levers during machine operation. The above locking mechanism has no effect on the year printing mechanism.

After the date setting levers have been properly positioned depression of the starting bar 66 locks them in position and releases the machine for operation. As herein before described, the leading frame 88 has a fixed movement back and forth and is rocked counter-clockwise (Fig. 5) during the first half cycle of machine operation and returns home in the last half cycle of operation. The reducing levers 507 under tension of 65 a plurality of springs 513 follow the leading frame 88 rearwardly, carrying with them the slides 503 and rotating the segments 509 counter-clockwise. These parts travel rearwardly as a unit until the projections 502 are brought in contact 70 with the studs 501 carried by the setting levers 491, 492 and 493, which stops the rearward movement of the slides 503 and the reducing levers 507 to properly position the date printing segments 509. After the printing segments have 75

thus been positioned the liner 95 engages the sectors 611 while an impression is being made, after which the leading frame 88 in its return movement picks up and returns the reducing levers 507 and the slides 503 to their normal positions.

Tally roll mechanism

In the present machine a copy or duplicate of every entry, is printed upon a tally web interposed between the printing type and the platen roll 65. Heretofore the practice has been to use thin transparent paper which was threaded between the type and the ink ribbon and when an impression was made the type would contact first the tally web, forcing it against the ink ribbon, and in turn forcing the ink ribbon against paper wound around the platen roll. This resulted in an impression being made upon the back of the tally web, which under ordinary circumstances could be read from the front because of the transparency of the tally web. In the instant machine a thicker and consequently more substantial tally web has been employed and impressions are made on the front of this paper in a manner to be later described.

Referring to Figs. 3 and 4, a supply roll of tally paper 514 is mounted on a friction reel 515 removably supported by a bracket 516 secured to the machine case 63. The tally web is first threaded under a roller 517, then through a chute 518, which directs the web below the traveling carriage, thence upwardly. Next the tally web is threaded between the two folds of the reflex ribbon 548 (Figs. 3 and 7) and continuing upwardly is attached to the core (Fig. 18) of a receiving or feeding roll 520. The receiving roll is turnably mounted upon a stud 521 (Figs. 3, 18 and 19) secured in a bracket 522 removably mounted on a post 523 secured to the machine case 63. A ratchet 524 is assembled between flanges 525 and 526, all of which are carried by the roll 520. The ratchet 524 is arranged to cooperate with a feed pawl 527 slidably mounted on the bracket 522 (Fig. 21) by being bifurcated to slip over a headed stud 530 secured in said bracket. The lower end of the feed pawl has a tail 531 (Figs. 18 and 19) with a right angled extension 532 which cooperates with an operating rod 533, the upper end of which extends through a slot in a printer top plate 534. The lower end of the rod 533 (Figs. 19 and 20) is bifurcated to receive a stud 535 in an arm 536 fixed to the shaft 80. The bracket 522 carries a stud 537 which cooperates with the tail 531 to guide the feed pawl 527. A spring 528 is tensioned to normally hold the feed pawl in contact with the teeth of the ratchet 524 and to urge said feed pawl downwardly in order to maintain the extension 532 in constant engagement with the tip of the operating rod 533. The bracket 522 (Fig. 19) carries a stud 538 upon which is pivoted a detent 539 having a roller 540 which is held in engagement with the teeth of the ratchet 524 by a spring 541. Referring to Figs. 19 and 20, the shaft 80 and arm 536 are rocked clockwise during the first half cycle of machine operation, allowing the rod 533 and the feed pawl 527 to be moved downwardly by the spring 528. During the last half cycle of machine operation the shaft 80 and arm 536 are returned counter-clockwise, forcing the rod 533 and the feed pawl 527 upwardly to rotate the ratchet 524 one tooth space and the feed roll 520 the same. This causes the tally web to be wound upon the receiving roll, which necessarily spaces said web as it is printed upon.

If desired, the tally web may be disabled in the following manner: Pivoted on the stud 538 (Figs. 3 and 21) is a disabling lever 542, its upper end terminating in a finger-piece 543 and having on its lower end a bent extension 544 adapted to cooperate with a projection 545 on the feed pawl 527. The lever 542 has embossed thereon a ball which is adapted to spring into a depression (not shown) in the bracket 522 to retain said lever in ineffective position, as shown in Fig. 21. Moving 10 the lever 542 counter-clockwise causes the extension 544 to engage the projection 545 and rock and retain the feed pawl 527 out of engagement with the teeth of the ratchet 524 to prevent feeding of the tally web during machine operation. 15 Moving the disabling lever 542 to effective position causes the ball to spring past the edge of the bracket 522 thus restraining the clockwise movement of said lever 542.

Paper injector mechanism

Means for manually rotating the platen roll at a high rate of speed have been supplied in the instant machine. This mechanism greatly facilitates insertion and ejection of material around 25 the platen roll 65. Following, a brief description will be given of this mechanism. Secured to the travelling carriage frame 64 (Figs. 10 and 12) by a dowel and a screw stud 555 is a plate 556 carrying a stud 557. A bifurcated lever 558 is composed of two symmetrical pieces 559 and 560 (Fig. 10) connected at the top by a handle 561 and at the bottom by a shouldered bushing 562 (Figs. 13 and 15). Rotatably mounted on the bushing 562 between the tines of the bifurcated 35 lever 558 is a gear 563 properly spaced between the tines by a pair of washers 564 (Fig. 13). A stop plate 565 has fast therein a stud 566 pivoted in holes in the tines of the lever 558. Mounted upon the stud 566 between the tines of the lever 40 558 is a feed pawl 567 carrying a stud 568 adapted to engage a hole 569 in the stop plate 565 to connect these two members as a unit. Mounted on either side of the pawl 567 (Figs. 11 and 14) is a pair of symmetrical friction plates 570, each 45 having an embossed gripping lug 571. The pawl 567 and gear 563 are about equal in thickness which causes the embossed portion of the gripping lugs 571 to embrace or grip the sides of said gear. The lever 558, gear 563 and pawl 567 and 50 stop plate 565 form a unit, which is pivoted by means of the bushing 562 on the stud 555, causing the teeth of the gear 563 to mesh with teeth of a pinion 578 fast on the platen shaft.

The bushing 562 is slotted (Figs. 13 and 15) 55 to receive one end of a spiral torsion spring 572, the other end of which extends within a slot in a cup 573 which houses said spring 572 and retains the lever 558 upon the stud 555 by being firmly held against the end of said stud by a screw 60 574. Tension may be placed on the spring 572 by revolving the cup 573 clockwise (Fig. 12) and then tightening the screw 574.

Due to the friction created by the gripping lugs 571, moving the lever 558 counter-clockwise causes the tooth of the feed pawl 567 to be immediately rocked into engagement with the teeth of the gear 563, causing said gear to rotate counter-clockwise in unison with said lever 558. This through the pinion 578 rotates the platen 70 roll clockwise at a much greater speed than is possible by using the knobs located at either end of the platen shaft. The counter-clockwise movement of the lever 558 and consequential 75 rotating of the platen roll 65 is arrested by

stop plate 565 coming in contact with the platen shaft. The spring 572 is tensioned to automatically return the lever 558 to home position, (Fig. 12) where the rounded ends of the feed pawl 567 and stop plate 565 engage the stop stud 557 in such a manner as to overcome the tendency of said feed pawl to engage the teeth of the gear 563 when the platen roll 65 is rotated counter-clockwise and the gear 563 clockwise, as viewed in Fig. 12, by means other than the lever 558. Likewise, the return movement of the lever 558 causes the friction lugs 571 in cooperation with the gear 563 to disengage the feed pawl 567 from the teeth of said gear so as to make a silent return of the lever 558.

Modified form

A modified form of vertical posting machine is illustrated in Figs. 44 to 50 inclusive. The material difference between the preferred and modified forms is that the latter has an off-set balance feature, wherein depression of the balance key causes the traveling carriage to tabulate slightly to the left so that balance entries will be printed out of alignment with other entries in the same column, thus facilitating the identification of balances which is advantageous in many ways.

In the modified form, the starting bar lock is controlled by stops on the traveling carriage, while in the preferred form, it will be recalled that this lock was controlled by the control keys for the different totalizers. Also, in the modified form, means for controlling the automatic tabulating feature by carriage stops and also by the balance key are provided. In the modified form, when the traveling carriage is in the off-set balance printing position, depression of either the deposit or check key, locks the starting bar against manipulation until such key is released. In the following detailed description, the mechanism of the modified form will be thoroughly treated.

Referring to Fig. 48, the shaft 372 has secured thereto an arm 575, shown in dot and dash lines. This arm is not used in the preferred form, otherwise, the assembly of the shaft 372 is identical in both forms. An offset balance key 576 (Figs. 49 and 50) has secured thereto a bracket 577 carrying a stud 580 which cooperates with a slot in an arm 581 secured on a shaft 582 journaled in the frames 60 and 61. Secured on the right end of the shaft 582 is an arm 583 which carries a flattened stud 584 arranged to cooperate with a bi-pass pawl 585 pivoted on a tabulating lever 586 pivoted at 587 to the right frame 61. The pawl 585 carries a stud which is retained against a projection on the lever 586, by a spring 598. The lever 586 has pivoted thereon another by-pass pawl 588 having a lug 632 normally held against the lower edge of the lever 586 by a spring 633. The pawl 588 is arranged to cooperate with a stud 589 in a tabulating key 590, the upper end of which extends through a slot in the keyboard plate 128. The upper end of the tabulating key 590 is reduced to form a shoulder which is normally held in contact with the keyboard plate 128 by a flat spring 591. The by-pass pawl 588 has an extension 592 adapted to cooperate with a stud 593 in the pitman 441 of the overdraft key 445. Depression of the overdraft key causes the stud 593 to move into the path of the extension 592 to block the clockwise or tabulating movement of the lever 586, thereby preventing tabulation during overdraft opera-

tions. The lever 586 has a slot 594 through which extends the tip of a tabulating beam 595 pivoted at 596 (Fig. 45) to the tabulating frame 152. The beam 595 cooperates with a stud 597 fast in a tabulating plunger 600 mounted to slide vertically in the tabulating frame 152. A spring 601 is tensioned to retain the plunger 600, beam 595 and lever 586 in their upward positions. Fast on the shaft 582 connected by a link 603 to an automatic tabulating disabling pawl 604 pivoted to the right frame 61 and having a hook arranged to cooperate with a stud 605 in an automatic tabulating hook 606 flexibly mounted on the link 84, (see also Fig. 2). The hook 606 (Figs. 49 and 50) is adapted to cooperate with a stud 607 in the tabulating lever 586. The upper end of the arm 575 cooperates with an extension 608 on a disabling cam lever 609 pivoted within a slot in a stud 610 secured in the right frame 61 and retained in effective position against a stud 611 by a spring 599. The lever 609 has a camming extension 612 which partially embraces the stud 607 to normally protect it from the hook 606. As set out hereinbefore, during normal machine operation, the link 84 reciprocates upward and back carrying with it the hook 606. When the lever 609 is in effective position, as here shown, the hook 606 rides idly over the extension 612 and is thus prevented from engaging the stud 607.

Interlock between the deposit and check keys and the starting bar

Calling attention to Figs. 47 and 48, in the modified form, there is an interlock between the deposit key 132 and the check key 144 and the starting bar 66 to prevent the depression of said starting bar when the traveling carriage is in the balance printing position, and either of the above keys is depressed. The studs 468 and 469 carried respectively by the keys 132 and 144 cooperate with the top edge of a lever 613 pivoted to the left frame 60. The lever 613 is bifurcated to embrace a stud 614 on an arm 615 secured to a shaft 616 journaled in the frames 60 and 61. Secured to the right-hand end of the shaft 616 is an arm 617 having pivoted on its upper end a wedge 618 with a tail 619 which extends between a stud 620 in the latch plate 375 and a stud 621 in an auxiliary latch plate 622 pivoted on the stud 376. The latch plate 622 has a shoulder 623 which cooperates with the stud 363 in the plate 257 in a manner to be later described.

Again directing attention to Fig. 45, the tabulating stop bar 127 carries a series of stops 624, each having two stopping lugs 625 adapted to cooperate with the plunger 600. Each stop 624 has a starting bar unlocking lug 626, a starting bar unlocking and automatic tabulating lug 627 and two add selecting lugs 628. The stops 624 are spaced along the bar 127 to correspond with the columnar divisions of a ledger sheet 629 (Fig. 44). As previously stated, there are two positions used in each column, one a listing position where old balances, deposits and checks are listed and the other a new balance printing position. In Fig. 45, the traveling carriage bar is shown in position for listing in the third column of the ledger sheet 629. In both the listing and balance printing positions, the No. 1 totalizer is constantly selected for addition by the lugs 628 coacting with the add hanging bar lever 159 for the No. 1 totalizer in the same manner as previously described for the preferred form. The constant selection of the No. 1 total-

izer for addition does not prevent other transactions such as subtract, sub-totalizing and totalizing from being carried on in this totalizer as these latter transactions supercede an additive one as previously described.

In the listing position, the lug 626 coating with the lever 381 rocks the shaft 372 (Fig. 48) counterclockwise and the lock plate 375 clockwise just enough to allow the stud 383 to clear the shoulder 382, thereby unlocking the starting bar 66. Likewise, the movement of the shaft 372 in listing position is not sufficient to cause the lever 575 (Fig. 50) to engage the extension 608. Obviously the plate 622 (Fig. 48) moves 10 in unison with the plate 375 because of the studs 620 and 621 and the tail 619 of the wedge 618. Depression of either of the keys 132 and 144 (Fig. 47) through the lever 613 rocks the shaft 616 and arm 617 clockwise forcing the wedge 20 618 upwardly to rock the plate 622 clockwise. This movement of the plate 622 has no effect when the traveling carriage is in listing position as the stud 383 still clears the shoulder 623. When the traveling carriage is tabulated to the 25 offset balance printing position, the shaft 372 receives additional counter-clockwise movement which in conjunction with either of the keys 132 and 144 locks the starting bar 66 against manipulation in a manner and for a purpose to 30 be later described.

After the listing of the deposits made and checks issued on a certain account for a given day it is then essential to balance the account, which is accomplished in the following manner. 35 Depression of the balance key 576 (Figs. 49 and 50) rocks the shaft 582 and arm 583 counterclockwise causing the stud 584 to engage the by pass pawl 585 to rock the tabulating lever 586 clockwise. This rocks the beam 595 clockwise (Fig. 45) forcing the plunger 600 downwardly to tabulate the traveling carriage. The engagement of the stud 584 with the pawl 585 is so timed that the plunger 600 is released to the tension of the spring 601 at the instant the 40 lefthand lug 625 begins to move over the top surface of said plunger. As soon as said lug 625 passes off the horizontal portion on top of the plunger 600, spring 601 forces the plunger 600 upwardly into the path of the right hand or 45 offset stopping lug 625 to stop the traveling carriage in the offset balance printing position.

As previously set out, the balance key 576 remains depressed until automatically released near the end of the machine operation whence 55 it is returned upwardly to home position by one of the springs 130 (Fig. 49). This also restores the shaft 582 and connecting mechanism, causing the stud 584 to wipe idly past the pawl 585 flexing the spring 598. Depression of the tabulating key 590 (Fig. 50) causes the stud 589 to engage the pawl 588 to rock the lever 586 clockwise to tabulate the traveling carriage in precisely the same manner as described for the balance key 576.

In the offset position, the lug 627 engages the lever 381 and as this lug is longer than the lug 626, the shaft 372 consequently rocks farther in a counter-clockwise direction when the traveling carriage is in the offset position than when said 60 traveling carriage is in the listing position. This causes the lever 575 (Fig. 50) to engage the extension 608 and rock the lever 609 to move the extension 612 out of the path of the hook 606 so that said hook will engage the stud 607 65 to move the lever 586 clockwise to automatically

tabulate the traveling carriage near the end of an operation.

Immediately following a balance operation, it is essential that the traveling carriage be retained in the offset position and in order to do this, it is necessary to cripple the automatic tabulating mechanism, which is accomplished in the following manner. The counter-clockwise movement of the shaft 582 and the arm 602, caused by the depression of the balance key 576, through the link 603 rocks the latch 604 clockwise into the path of the stud 605 on the hook 606. This prevents the hook 606 from engaging the stud 607 thus crippling the automatic tabulating mechanism.

The increased movement of the shaft 372 (Fig. 48) when the traveling carriage is in the offset balance printing position causes the locking plates 375 and 622 to be moved to a position where depression of either the deposit key 132 or the check key 144 will through the wedge 618 and its connections force the shoulder 623 into the path of the stud 383 to lock the starting bar 66 against manipulation. This prevents the listing of deposits or checks in the offset balance printing position. A spring 634 is tensioned to restore the shaft 616 to and retain it in its normal ineffective position when the keys 132 and 144 are released. With the carriage in the "offset" position, where it is left after a "balance" operation, the lock 375-622 is held in its unlocking position, so that the motor bar 66 is free to be depressed. If the operator should forget to move the carriage into the listing position prior to a subsequent listing operation, an incorrect entry 30 will be made. In order to warn the operator that he has made an improper entry, the automatic tabulating mechanism including the hook 606 operates to lower the tabulating lever 586 at the end of the operation to tabulate the carriage to its new position. This operation is possible because at this time the member 612 is held moved by the carriage and as the balance key is not depressed the hook 604 is held ineffective. Further improper entries are then not possible because in the tabulated positions it is necessary to depress a control key to unlock the motor bar. 40

The overdrawn balance is also printed in the offset position, but in order to obtain this result it is necessary to depress the tabulating key 590 before depressing the overdraft key 445. Depression of the tabulating key causes the carriage to tabulate to the offset position in the manner hereinbefore described.

Special printing keys

Situated to the right of the amount keys, 121 (Fig. 1) is a row of special keys 635 which are printing keys only and control a printing segment 631 (Fig. 7) which prints symbols or letters used for the identification of certain entries. When used in connection with the check key 144, these symbols or letters have a certain interpretation and when used in connection with the deposit key 132, they have another interpretation. These interpretations are given at the top of ledger sheets 274 and 629 (Figs. 42 and 44) and are exactly the same in both the preferred and modified forms.

Operation

The systems used in connection with the machines of both the preferred and modified forms are similar and nearly self-explanatory. Therefore, they will be jointly treated in the following brief description. In the systems used with both

forms of machines, every entry is printed upon the tally strip, a fragment of which is shown in (Fig. 46). This tally strip is retained as a matter of record and for verifying or checking purposes.

5 As set out herein before, the tally web is interposed between the two folds of the reflex bichrome inking ribbon which in turn passes in front of any material wound around the platen roll 65. The ribbon, the tally web and the ledger sheet 10 are all interposed between the printing segments and the platen roll, which results in duplicate entering of items on the tally web and ledger sheet with a single movement of the printing segments.

15 Referring to Fig. 42, which illustrates the ledger sheet for the preferred form, let us assume an account was opened on July 6, 1931 by depositing \$500.00 to the credit of John Doe. This is accomplished by setting up the amount on the 20 keyboard and depressing the deposit key 144 and releasing the machine for operation by depressing the starting bar 66. Near the end of each machine operation, the platen roll and tally web are line spaced automatically. Next let us assume that on the same date, July 6, five checks 25 were issued against this account, one for \$35.00, another for \$40.00, a third for \$30.00 and a fourth for \$20.00, and a fifth for \$10.00. These checks were subtracted from the \$500.00 deposit and simultaneously added in the No. 3 totalizer. This 30 constitutes all the deposits and withdrawals for July 6 so the operator balances the account by depressing the balance key 292 (Fig. 1) which selects the No. 1 accumulator for a total operation and simultaneously selects the No. 2 accumulator for addition.

As previously stated, each account is balanced daily so on July 7, 1931, the account of John Doe is again balanced. First, the old balance of 40 \$365.00 is set up on the keyboard and added into the No. 1 totalizer and in this case, the sub-total key 392 is used to unlock the starting bar 66, in order to prevent the old balance pick-up from being added into the No. 4 totalizer. The 45 deposits are added to and the checks subtracted from this amount as before and finally a balance operation is made, the result being \$526.00.

In case an account is overdrawn, the operator is notified of this fact by inability to depress the 50 balance key. It then becomes necessary to perform an overdraft operation. First, the sub-total key is depressed which releases the depressed deposit or check key and also unlocks the starting bar 66. Next, the overdraft key 445 is depressed, 55 which causes the machine to operate through the three cycles necessary to print the positive amount of the overdraft. Usually at the end of a day's run, the different totalizers are cleared and the total checks, total deposits, and total balances 60 printed upon the tally web, as a record for verifying or checking purposes.

The only material difference in the systems of the preferred and modified forms is that depressing the balance key 576 of the modified 65 form causes the traveling carriage to tabulate slightly to the left in order to print the balance out of alignment with other entries. In the system of the modified form, the old balance of an account is picked up and added into No. 1 70 totalizer before the ledger sheet for such account is inserted in the machine. This results in the old balance being printed on the tally web only. This latter step, however, is discretionary and if desired, may be used in either 75 system.

While the forms of mechanism herein shown and described are admirably adapted to fulfill the objects primarily stated, it is to be understood that it is not intended to confine the invention to the forms of embodiment herein disclosed, for it is susceptible of embodiment in various forms all coming within the scope of the claims which follow.

What is claimed is:

1. In a machine of the class described, having an add-subtract totalizer and a traveling carriage, the combination of a subtract key; an adding key; means for releasing the machine for operation; means for normally locking the releasing means against operation; means operable by the traveling carriage, in certain tabulated positions thereof, for rendering the locking means ineffective, and means whereby the traveling carriage in another tabulated position thereof locks the releasing means when either key is in depressed position.

2. In a machine of the class described having an add-subtract totalizer and a traveling carriage, the combination of subtract conditioning means; add conditioning means; machine releasing means; means controlled by the traveling carriage in tabulated positions for locking the releasing means when either the add or subtract conditioning means is in effective position.

3. In a machine of the class described having an add-subtract totalizer and a traveling carriage, the combination of a subtract key; an add key; machine releasing means; means for normally locking the releasing means; means controlled by the traveling carriage in certain tabulated positions thereof for rendering the locking means ineffective; and means controlled by the traveling carriage in other tabulated positions for locking the releasing means when either key is in effective position.

4. In a machine of the class described having an add-subtract totalizer and a traveling carriage, the combination of subtract conditioning means; add conditioning means; machine releasing means; means for normally locking the releasing means; means operable by the traveling carriage in certain tabulated positions thereof for unlocking the releasing means; and means operable jointly by either of the conditioning means and the traveling carriage, in other tabulated positions thereof, for locking the releasing means.

5. In a machine of the class described having an add-subtract totalizer and a traveling carriage, the combination of subtract conditioning means; add conditioning means; machine releasing means; and means operable jointly by either one of the conditioning means and the carriage for locking the releasing means.

6. In a machine of the class described having an add-subtract totalizer and a traveling carriage, the combination of subtract conditioning means; add conditioning means; machine releasing means; and means operable by the traveling carriage in certain tabulated positions for locking the releasing means when either of the conditioning means is in effective position.

7. In a machine of the class described having an add-subtract totalizer and a traveling carriage, the combination of add conditioning means; subtract conditioning means; machine releasing means; locking means for the releasing means; means operable by the traveling carriage in certain tabulated positions for rocking the locking means part-way toward effective position.

sition; and means operable by either of the conditioning means for rocking the locking means the remaining distance to effective position.

8. In a machine of the class described having an add-subtract totalizer and a traveling carriage, the combination of add selecting means; subtract selecting means; machine releasing means; locking means for the releasing means; means operable by either of the selecting means for moving the locking means part-way toward effectiveness; and means operable by the traveling carriage in tabulated positions thereof for moving the locking means the remaining distance to effective position.
15. 9. In a machine of the class described having an add-subtract totalizer and a traveling carriage, the combination of add key means; subtract key means; machine releasing means; normally effective locking means for the releasing means; normally ineffective locking means for the releasing means; means operable by the traveling carriage in tabulated positions thereof for rendering the first mentioned locking means ineffective and simultaneously moving the second locking means part-way toward effective position; and means operable by either of the key means when depressed for rocking the second locking means the remaining distance to effective position.
30. 10. In a machine of the class described having an add-subtract totalizer and a traveling carriage, the combination of add key means; subtract key means; machine releasing means; normally effective locking means for the releasing means; normally ineffective locking means for the releasing means; means for coupling the two locking means to prevent the first mentioned locking means from moving independently of the second locking means but said second locking means being free to move independently of the first mentioned locking means; means controlled by the traveling carriage in predetermined tabulated positions for rocking both locking means to an intermediate position where neither are effective; and means controlled by either the add or subtract key means for rocking the second locking means to effective position when the traveling carriage is in predetermined tabulated positions.
55. 11. In a machine of the class described, having an add-subtract totalizer and a traveling carriage, the combination of add selecting means; subtract selecting means; machine releasing means; normally effective locking means for the releasing means; normally ineffective locking means for the releasing means; and means for coupling both the locking means to prevent the normally effective locking means from moving independently of the normally ineffective locking means, said normally ineffective locking means being free to move independently of the first mentioned locking means.
60. 12. In a machine of the class described having an add-subtract totalizer, a traveling carriage, and means for automatically tabulating the traveling carriage; the combination of total-taking means; and means whereby manipulation of the total-taking means snap tabulates the traveling carriage and simultaneously locks the automatic tabulating mechanism in ineffective position.

70. 13. In a machine of the class described having an add-subtract totalizer, a traveling carriage and normally disabled automatic tabulating means for said traveling carriage, the combination of total-taking means for the add-subtract

totalizer; means whereby the traveling carriage in certain tabulated positions enables the automatic tabulating mechanism; and means operable by the total-taking means for rendering the automatic tabulating mechanism ineffective during total operations.

14. In a machine of the class described having an add-subtract totalizer, a traveling carriage, a normally disabled automatic tabulating mechanism, and a manual tabulating mechanism for the traveling carriage, the combination of total-taking means normally in ineffective position; means operable by the traveling carriage in certain tabulated positions for enabling the automatic tabulating mechanism; and means whereby the total-taking means when moved to effective position causes the traveling carriage to tabulate to said certain positions and simultaneously renders ineffective the automatic tabulating mechanism during a total operation.

15. In a machine of the class described having an add-subtract totalizer, a traveling carriage, a normally disabled automatic tabulating mechanism and a manual tabulating mechanism, the combination of total-taking means; means operable by the traveling carriage in certain tabulated positions for enabling the automatic tabulating mechanism; means operable by the total-taking means for tabulating the traveling carriage to said certain positions; and means operated by the total-taking means for locking the automatic tabulating means during total-taking operations.

16. In a machine of the class described having an add-subtract totalizer, the combination of an add key; a subtract key; latch means for each of the keys; total-taking means; a projection on the total-taking means; and a pivoted member intermediate the latch means and the total-taking means, one end of which cooperates with the projection on the total-taking means, the other end cooperating with both the latch means so that moving the total-taking means to effective position releases the operated add or subtract key and retains the latch means ineffective during machine operation.

17. In a machine of the class described having an add-subtract totalizer, the combination of add key means; subtract key means; a latch for each of the above key means; total key means; a projection on the total key means; and a pivoted member adapted to cooperate with the latch means and the projection on the total key so that depression of the latter disables the latch means thereby releasing the operated add or subtract key means.

18. In a machine of the class described having an add-subtract totalizer, the combination of add key means; subtract key means; a latch for each of the above key means; total key means; a projection on the total key means; a member intermediate the latch means and the total key means, one end of which cooperates with the projection on the total key means, the other end arranged to cooperate with the latch means, so that depression of the total key means releases the depressed add or subtract key means by restoring the latch means to normal position.

19. In a machine of the class described having an add-subtract totalizer, the combination of add key means; subtract key means; latch means for each of the above key means; a lever operatively connected to the subtract key means; a projection on the lever adapted to cooperate with the add key latch; and a projection on the

add key means adapted to cooperate with the subtract key latch for the subtract key means so that when one of the key means has previously been depressed, depression of the other key means 5 restores the latch means for the former to release the depressed key.

20. In a machine of the class described having an add-subtract totalizer, the combination of add key means; subtract key means; latch means for 10 each of the above key means; sub-total key means; total key means; and means intermediate the add and subtract key means and the sub-total and total key means for releasing the operated one of the former when either of the latter 15 is effective.

21. In a machine of the class described having an add-subtract totalizer, the combination of add selecting means; subtract selecting means; latch means for each of the selecting means; 20 total-taking means; sub-total taking means; a projection on the total and sub-total-taking means; and a pivoted member one end of which cooperates with projections on the total and 25 sub-total-taking means, the other end adapted to cooperate with the latches for the selecting means so that moving either the total or sub-total-taking means to effectivity releases the operated add or subtract selecting means and retains both the latch means ineffective during 30 total or sub-total operation.

22. In a machine of the class described having an add-subtract totalizer, an automatic overdraft device therefor and means for releasing the machine for operation, the combination of 35 add conditioning means; subtract conditioning means; overdraft conditioning means; means for

normally locking the machine releasing means in ineffective position; means operatively connecting the overdraft conditioning means to the machine releasing means; means for locking the overdraft conditioning means when either the add 5 or subtract conditioning means is effective; and means for rendering ineffective the add and subtract conditioning means and simultaneously unlocking the releasing means so that the overdraft conditioning means may be moved to effective position and the releasing means actuated.

23. In a machine of the class described having a plurality of totalizers and a shiftable bichrome ribbon means, the combination of subtract key means; latch means for the key means; and 15 means whereby depression of the subtract key means causes the latch means to control means to simultaneously condition one totalizer for subtract operation, another totalizer for add operations, and shift the ribbon mechanism to a position where subtract entries will be printed in a distinctive color. 20

24. In a machine of the class described having an add-subtract totalizer, and arranged to make entries in vertical alinement, the combination of 25 printing means; a traveling carriage adapted to be tabulated to different positions; automatic tabulating mechanism; total-taking means; means operable by the total-taking means for tabulating the traveling carriage so that totals 30 will be printed out of alinement with other entries; and means operable by the traveling carriage when tabulated to total-printing position for rendering the automatic tabulating mechanism effective. 35

RAYMOND A. CHRISTIAN.
